UNITED STATES PATENT OFFICE

140,233

DESIGN FOR A BOTTLE CAPPER HEAD

Rudolph Sonnenberg, Belvidere, Ill., assignor to
Mid-West Bottle Cap Co., Belvidere, Ill., a cor-
poration of Illinois

Application July 27, 1944, Serial No. 114,578

Term of patent 14 years

(Cl. D2—3)

To all whom it may concern:

Be it known that I, Rudolph Sonnenberg, a citizen of the United States, residing at Belvidere, in the county of Boone and State of Illinois, have invented a new, original, and ornamental Design for a Bottle Capper Head, of which the following is a specification, reference being had to the accompanying drawings, forming part thereof.

In the drawings:

Figure 1 is a side perspective view of a bottle capper head showing my new design;

Fig. 2 is a front elevational view thereof;
Fig. 3 is a fragmentary elevational view of the side opposite that of Fig. 1 with portions shown broken away for convenience of illustration, and
Fig. 4 is a top plan view thereof.

I claim:

The ornamental design for a bottle capper head, substantially as shown.

RUDOLPH SONNENBERG.
